CHARLES S. BOSSIE, OF NEW YORK, N. Y., ASSIGNOR TO PERFECTION APPLIANCES INC.,
OF NEW YORK, N. Y., A CORPORATION OF NEW YORK

WASHING MACHINE

Application filed July 21, 1930. Serial No. 469,298.

This invention relates to a washing machine.

The object of the invention is the production of a washing machine, which can be easily adjusted for use in washtubs or other receptacles of different sizes. The second object of the invention is the production of a washing machine wherewith the objects washed are subjected to the combined effect 10 of suction plungers and an agitator. The third object of the invention is the production of a washing machine wherein a pair of suction plungers and an agitator are simultaneously operated. The fourth object of 15 the invention is the production of a washing machine adapted to support and operate a clothes wringer. The fifth object of the invention is the production of a washing machine adapted to support and rotate a cleaning wheel for pots, pans and the like. The sixth object of the invention is the production 20 of a washing machine, which is independent of the washtub or other receptacle with which it is used. The seventh object is the production of a washing machine of 25 which portions can be folded and other portions easily dismantled to locate the machine in an ordinary washtub or receptacle and thereby save space, and make the machine invisible when not in use. The eighth 30 object of the invention is the production of a washing machine for washing clothes, underwear, or other fabrics easily, and which avoids the filling of the machine with water and draining the same from the machine.

The present invention is an improvement of my washing machine described in my Letters Patent No. 1,708,931, dated April 16, 1929.

40 In the accompanying drawings Fig. 1 represents a front elevation of an exemplification of the washing machine, in operative position in a washtub indicated in vertical section; Fig. 2 shows a top plan view and section of Fig. 1 on the line 2, 2; Fig. 3 indicates a section of Fig. 1 on the line 3, 3; Fig. 4 shows a section of Fig. 2 on the line 4, 4; Fig. 5 shows a fragmentary portion of an oscillating beam; Fig. 6 represents an elevation of 45 a locking link and Fig. 7 indicates a frag-

mentary portion of an oscillating shaft with a support.

The washing machine in this instance is indicated to comprise a platform designated in its entirety by the numeral 20. A journal bracket is formed with an extends up from said platform, and comprises the longitudinal wall 21 which has integral therewith the flanges 22 and 23. Journal bearings 26 are integral with the flanges 22 and 23. The journal block 28 and the journal block 29 having the clearance recess 30 are supported upon and fastened to the platform 20. A locking plug 32 is fastened to the upper face of the journal block 29. A journal bracket 35, having the journal bearings 36 and 37 is supported upon and fastened to the platform 20. A journal bracket 38 extends up from and is integral with the platform 20. A worm shaft 40 is journaled at one end in the journal bearings 26 and has fastened thereto the worm 41. A collar 42 is fastened to the worm shaft 40 and bears against one of the journal bearings 26. A shaft 43 is journaled in the journal bracket 38 and in the longitudinal wall 21. One end of shaft 43 has formed therewith the projection 44. To the other end of the shaft 43 is fastened the hub end of the arm 45. A worm wheel 46 is fastened to the shaft 43 and meshes with the worm 41. A link 48 has one end pinned to the arm 45 by means of the pin 49. In the journal blocks 28 and 29 is journaled the horizontal oscillating shaft 50. To one end of the shaft is fastened one end of the arm 51, and the latter is pinned to the link 48, by means of the pin 52. To the other end of the shaft 50 is fastened the cylindrical support 58, having the recesses 59 in the opposite sides thereof. A spindle 60 is supported in the journal bearings 36 and 37. An arm 61 has its upper end fastened to the spindle 60, and the lower end of the arm 61 is bifurcated. A bent link 62 has one end pinned to the bifurcated end of the arm 61 and its other end is pinned to the arm 51, by means of the pin 63. To the other end of the spindle 60 is fastened the arm 65, which is also bifurcated at its lower end. A twisted link 68 has one end pinned to the arm 65 by means of the pin 69. 100

In the clearance recess 30 of the journal block 29 is located the arm 70 which is pivoted at one end to the vertical pivot 71 extending from said journal block 29. The other end of the arm 70 is pinned to the twisted link 68 by means of the pin 72. In the wall 21 is journaled a shaft 76, which at one end has fastened thereto the bevel gear 77, which meshes with the bevel gear 78 fastened to the worm shaft 40. The shaft 76 has fastened thereto the hub 79 against which bears the clamping disc 80. The outer end of the shaft 76 has formed therewith the threaded shank 81. A second clamping disc 82 is supported on the shaft 76, and a nut 83 is supported on the threaded shank 81. The clamping discs 80 and 82 may be spaced from each other and a cleaning wheel, not shown, may be clamped between the discs 80 and 82 in conjunction with the nut 83. To the wall 21 is bolted the supporting bracket 85, by means of which one end of a clothes wringer, not shown, may be supported. The projection 44 of the shaft 43 may be attached 25 to a rotating element of the clothes wringer to actuate the latter.

To the lower face of the platform 20 are detachably bolted, by means of the bolts 88, a pair of similar supporting brackets, designated in their entireties by the numerals 90 and 91. The supporting bracket 90 has formed therewith the upper flange 92, having the elongated opening 93 for its bolt 88, and the supporting bracket 91 has formed therewith the upper flange 94 having the elongated opening 95 for its bolt 88. The flange 94 and its opening 95 are somewhat longer than the flange 92 and the opening 93, for convenience in locating the machine in operative position 40 in the washtub, designated in its entirety by the numeral 96. The washtub is shown having the side walls 97, rear wall 98 and the bottom wall 99. The front wall of the washtub is not shown. From each of the flanges 45 92 and 94 extends the vertical member 101 having the bifurcated journal bearing 102. A leg is pivoted to each of the members 101 and is indicated having the lower member 105 and the upper member 106. The member 105 has formed therewith the heel 107 and at its lower end is formed the sleeve 108. The member 106 has extending from one face of its upper end the boss 109. To the other face 50 of the member 106 is fastened the plug 110 of rubber or other flexible material. In the sleeve 108 is detachably secured the rod 114, to the lower end of which is secured the cap 115 of rubber or other flexible material. Between the members 105 and 106 is formed the 55 journal bearing 116 which is pivoted to the bifurcated journal bearing 102, by means of the pin 118. A latch arm 120 has the bifurcated upper end 121, which is pivoted to the vertical member 101 by means of the pin 122. The lower end 123 of each latch arm 120 is

adapted to lock with the heel 107 of its coacting member 105, when the latter is positioned in its operative open position.

A pair of stems are shown at 130 and to their lower ends are fastened the cup-shaped suction plungers 131. To the upper ends of the stems 130 is pinned the oscillating beam 132, which has formed therewith the handle 133. The latter has formed therewith at its lower end the prongs 134 having the straight vertical inner walls 135, that engage the recesses 59 of the support 58. A link 136 parallel to the beam 132 is also pinned to the stem 130. A locking link 137 is indicated having the lug 138 at its lower end and the lug 139 at its upper end. The link 137 is pivoted to the link 136 by means of the pin 141. The lug 139 has formed therein a rectangular opening 140 which is adapted to seat on the locking plug 32 and prevents the accidental disengagement of the oscillating beam 132 from the support 58 when said beam is in a tilted position. The link 137 also prevents the beam 132 rising too high from its support 58.

To the lower end of the vertical pivot 71 is detachably fastened an agitator comprising the upper tubular end 144 of the agitator stem 145. A cross bar 146 extends through and is fastened to the lower end of the agitator stem 145. Prongs 147 extend from the cross-bar 146.

An electric motor 150 is supported upon and fastened to the journal blocks 28 and 29, and the worm shaft 40 is coupled to the armature shaft 152 of said electric motor. A switchboard 151 for said electric motor is fastened to the platform 20. A cover 155 is supported on the platform 20 to cover the essential portions of the mechanism of the washing machine above the platform 20.

To use the washing machine it is located in the washtub 96 with the caps 115 of the rods 114 bearing on the bottom wall 99 of said tub. The plugs 110 of the members 106 of the legs are located to bear against the rear wall 98 of the washtub. The washtub 96 is partly filled with water and soap or other washing ingredients and the clothing or other objects to be washed are immersed in the water in the tub.

The electric motor 150 is started, whereby the worm shaft 40 and worm 41 rotate. The worm 41 rotates the worm wheel 46. The worm wheel 46 revolves the arm 45, and the link 48 transmits oscillation to the arm 51, and the oscillating shaft 50 is thereby caused to oscillate. The oscillating beam 132 oscillates with the shaft 50, and with the oscillations of the beam 132 the cup-shaped suction plungers 131 are caused to reciprocate and bear on and rise up from the material operated upon. When the said suction plungers rise, a suction effect is produced

which draws the dirt and other foreign matter from the material operated upon.

The oscillations of the arm 51 are transmitted to the arm 61 through the bent link 62, and thereby the spindle 60 is oscillated. The spindle 60 oscillates the arm 65 and the latter reciprocates the twisted link 68. The link 68 swings the arm 70 and the latter oscillates the pivot 71, whereby the cross-bar 146 of the agitator stem 145 is oscillated. The cross bar 146 of the agitator being below and adjacent to the suction plungers 131 functions with the latter to circulate the water around and through the material operated upon, and also to move said material.

The bevel gear 78 transmits rotation to the bevel gear 77 whereby rotation is imparted to the shaft 76, and the cleaning wheel, not shown, supported on said shaft 76 is thereby turned.

It will be noted that this improved washing machine has no washtub integral therewith, and thereby avoids the necessity of draining any soiled water from the machine.

25 The legs having the members 105 and 106 can be swung on the pins 118 to locate the members 105 adjacent to the platform 20, when the machine is not in use. Also the oscillating beam 132 with the suction plungers 131 30 and the agitator 145 can be easily dismantled when the machine is not in use and located with the remainder of the washing machine in a washtub or other receptacle. The rods 114 can be adjusted to extend at different 35 lengths from the sleeves 108 for washtubs of different depths, and function as extensions of the members 105 of the legs.

Various modifications may be made in the invention and the present exemplification is 40 to be taken as illustrative and not limitative thereof.

Having described my invention what I desire to secure by Letters Patent and claim is:

1. In a washing machine the combination 45 of a pair of suction plungers, means to reciprocate the plungers, an agitator adjacent to the suction plungers, said agitator comprising an agitator stem, a cross bar fastened to the lower end of the agitator stem, prongs extending from said cross bar and means to oscillate said agitator stem while the suction 50 plungers reciprocate.

2. In a washing machine the combination 55 of an oscillating shaft, an oscillating beam supported on one end of the shaft, a pair of stems having their upper ends pinned to the oscillating beam, a suction plunger fastened to the lower end of each stem, a spindle supported in the machine, connections between 60 said shaft and said spindle to oscillate the latter, an arm having its upper end fastened to the spindle, a link having one end pinned to the lower end of said arm, a pivot supported in the machine, an arm having one end 65 fastened to said pivot and its other end

pivoted to the link and an agitator fastened to said pivot.

3. In a washing machine the combination of a platform, a pair of supporting brackets 75 slidably connected to the lower face of the platform, a leg comprising an upper member and a lower member pinned to each bracket, a heel formed with the lower member of each leg, a boss extending from one face of the upper member of each leg adapted to bear on its adjacent bracket, a plug of flexible material positioned against the other face of each upper member of each leg, the said plugs of flexible material adapted to bear against the wall of a washtub, a latch arm for each of 80 said brackets and having its upper end pinned thereto, the lower end of each latch arm adapted to lock with the heel of its adjacent leg, a rod adjustably connected to the lower member of each leg, to constitute an extension 85 of said lower member of each leg and a flexible cap attached to the lower end of said rod.

4. In a washing machine the combination 90 of a platform, a pair of supporting brackets slidably connected to the lower face of the platform, a leg comprising an upper member and a lower member pinned to each bracket, a heel extending from the lower member of each leg, a latch arm for each of said brackets 95 and having its upper end pinned thereto, the lower end of each latch arm adapted to lock with the heel of its adjacent leg, and a rod adjustably connected to the lower member of each leg to constitute an extension 100 therefor.

5. In a washing machine the combination 105 of an oscillating shaft, an oscillating beam supported on one end of the shaft, a pair of stems having their upper ends pinned to the oscillating beam, a suction plunger fastened to the lower end of each stem, a pivot supported in the machine, an arm having one end fastened to said pivot, connections between the other end of said arm and said oscillating shaft to swing said arm and an agitator fastened to said pivot, said agitator oscillating with the swinging of said arm.

Signed at the borough of Manhattan, city of New York in the county of New York and State of New York this 12th day of July, 115 A. D. 1931.

CHARLES S. BOSSIE.
